[57] CLAIM

The ornamental design for an organizer case, showing my new design.

DESCRIPTION

FIG. 1 is a top plan view, organizer case in open position, of my organizer case showing my new design;

FIG. 2 is a top plan view thereof, outer surface of my organizer case in open position;

FIG. 3 is a side view of FIG. 2;

FIG. 4 is a side view of FIG. 1;

FIG. 5 is an end view of FIG. 2;

FIG. 6 is an end view of FIG. 1; and,

FIG. 7 is a top plan view of my new design in open position with the organizer in extended position (non-extended position shown in FIG. 1).
